UNITED STATES PATENT OFFICE.

CHESTER H. THORDARSON, OF CHICAGO, ILLINOIS.

ATTACHMENT FOR SPARK-COILS.

1,043,274.

Specification of Letters Patent.

Patented Nov. 5, 1912.

Application filed June 29, 1908. Serial No. 440,845.

To all whom it may concern:

Be it known that I, CHESTER H. THORDARSON, a citizen of the United States, residing at Chicago, in the county of Cook, State of Illinois, have made a certain new and useful Invention in Attachments for Spark-Coils, of which the following is a specification.

The invention relates to spark coils and more particularly to attachments for spark coils.

The object of the invention is to provide an attachment which may be readily applied to and removed from the casing or other convenient part of a spark coil, and which attachment carries the vibrator for making and breaking the circuit of the coil.

A further object is to provide means whereby the vibrator for spark coils may be quickly removed from the coil for repair or replacement without disturbing any of the other parts of the coil thereby enabling repairs to be made to the vibrators of individual units of a bank of coils without removal of such unit from the bank.

A further object is to provide a vibrator attachment for spark coils which is simple in construction and economical to manufacture.

Other objects of the invention will appear more fully hereinafter.

The invention consists substantially in the construction, combination, location and relative arrangement of parts, all as will be more fully hereinafter set forth, as shown in the accompanying drawings and finally pointed out in the appended claims.

Referring to the accompanying drawings, and to the various views and reference signs appearing thereon. Figure 1 is a view in end elevation of a spark coil showing the application thereto of a removable vibrator attachment constructed in accordance with my invention. Fig. 2 is a broken view in central longitudinal section. Fig. 3 is an enlarged central longitudinal section, on the line 3, 3, Fig. 1, of the removable vibrator attachment. Fig. 4 is an end view of the construction shown in Fig. 3. Fig. 5 is a view in transverse section on the line 5, 5, Fig. 1. Fig. 6 is a fragmentary view of the end plate or cap of the coil casing showing means for receiving and retaining the removable vibrator attachment. Fig. 7 is an attached detail view in perspective of an

angle plate employed in connection with my invention.

The same part is designated by the same reference sign wherever it occurs throughout the several views.

In the use of spark coils it frequently becomes necessary and advisable to repair or replace the parts which constitute the vibrator or circuit breaker, as these are the parts which are most liable to burn or to wear out or get out of order. The parts of the coil itself are not so delicate and hence require but very little attention or care for repair or replacement of parts thereof. In order to effect a repair or renewal of the parts of the vibrator or circuit interrupter it has heretofore been necessary to remove the entire coil and its casing. This is undesirable, especially where the coil forms an individual unit in a bank of coils. It is among the special purposes of my present invention to provide an attachment which carries the vibrator or circuit interrupter and which can be readily removed from or replaced in operative position with reference to the coil or its casing. By thus providing the vibrator or interrupter mechanism in the form of a separate attachment, and means by which such attachment can be readily and quickly applied to and removed from the coil casing, it will be seen that I am enabled to remove the attachment for repair or replacement of any of its parts without deranging the coil or without removing the coil as a unit in the bank of coils. It will also be seen that the vibrator mechanisms or attachments can be readily carried in stock or as spare parts and when the necessity arises for immediate repair or replacement the defective attachment may be removed and a new one applied in its place, leaving the removed defective attachment to be repaired at leisure or returned to the shop.

The construction of the coil and its casing, except as hereinafter noted, in the details thereof forms no part of my present invention. I have shown the invention applied to the form of coil and casing as disclosed in my Patent No. 899,634, dated Sept. 29, 1908, and wherein the coils 7, 8 the magnet 9, and core 10, are suitably arranged, located and insulated wholly within the casing 11. It is obvious that other forms, constructions and arrangements are equally well

adapted for use in connection with my invention.

The top or cover or other convenient part of the coil casing, indicated at 12, is formed 5 or provided with an upturned lip 13, at or adjacent one end thereof, while at or adjacent the other end thereof, said top or cover is provided with an opening therethrough, indicated at 14, which is covered by insulating sheets of mica, or other suitable material, indicated at 15, 16, applied to the under as well as the upper sides respectively, of such top or cover. On the under side of the insulating sheet 15 is applied a 10 conducting plate 17, and to the upper side of insulating sheet 16 is applied a conducting plate 18. The conducting plates 17, 18, are in electrical contact with each other, as for instance by means of lips 19, formed on the edges of the plate 18, which lips are 15 bent down and pass through the opening 14, and through the insulating sheets 15, 16, and engage underneath the conducting plate 17, clearly shown. The plate 17, may be 20 further retained by lips 20, bent down from the body of the top or cover 12, and engaging on opposite sides of the plate 17, the insulating sheet 15, having its edges turned down between the lips 20, and the edges of 25 plate 17, to efficiently insulate said plate from the top or casing. Similarly, the top or casing 12, is provided with an upturned flange 21, against which bears the upturned portion 22 of plate 18, which is in the form 30 of an angle plate, the insulating sheet 16, being upturned at its end, as at 23, to insulate the flange 22, from lip 21. The conductor plate 17, is provided with a depending projection or finger 24, to afford means for 35 effecting electrical connection with the circuit terminal of the magnet coils.

The removable circuit breaker or vibrator attachment includes a frame plate 25, having at one end a downward lip 26, adapted 40 to removably or detachably engage under the upturned lip 13, of the top or casing 12. The frame plate 25, is cut out centrally, as indicated at 27, Fig. 1, to accommodate the vibrating armature 28. This armature is 45 supported by a spring plate 29, in any suitable manner, as, for instance by means of tongues 30, bent up from the armature and clenched to the spring plate 29, as clearly shown in Fig. 3. The armature supporting 50 spring plate 29, is clamped and held at one end between clamp plates 31, 32, mounted upon a clamp bolt 33. This clamp bolt passes through an upturned flange 34, of the attachment plate 25, but is insulated therefrom, being screwed into a plate 35, placed 55 on the upper side of the flange 34, with an interposed insulating sheet 36, therebetween. A spring contact strip 37, is clamped and held at one end between the clamp 60 plate 32, and an overlying plate 38, which is

mounted on the clamp bolt 33, a sheet of insulation 39 being placed over the plate 38, and held in place by the strip 40, the edges of the insulating sheet 39, being bent down over depending flanges of the contact strip 37, to afford efficient insulation therefor from the attachment supporting plate 25.

From the foregoing description it will be seen that all the parts carried, held or clamped by the clamp bolt 33, are supported 75 upon but insulated from the attachment supporting plate 25.

The upturned flange 22, is provided with an opening therein designed to snap over a shoulder or projection 41, formed in the upturned flange 42, of clamp plate 38, so that by deflecting the flange 22, until said shoulder or projection 41, is disengaged, the entire attachment plate, with all the parts carried thereby, may be readily detached and 80 removed by simply disengaging the tongues 26 and 13, and a new attachment plate with its associated parts applied by engaging the tongue 26, thereof underneath the tongue 13, at one end of said plate, and then depressing 85 the other end until the shoulder 41, snaps into engagement with the flange 22.

Cooperating with the contact strip 37, is a terminal screw 43, against which said strip normally bears and makes electrical contact, and which is designed to receive the circuit wire connection. This screw is carried by an overhanging flange 44, of the attachment plate 25. The armature 28, is provided with an overturned lip 45, underneath which the free end of contact strip 37, works, and an adjustable screw 46, serves to 90 form a limit stop to regulate the limit of vibratory movement of the armature in one direction, said limit screw being carried by 95 the overhanging portion 44, of the body plate 25.

When the removable attachment is applied in position for use the contact plate 31, of the attachment bears directly upon 100 the contact plate 18, carried by the top or casing 12, and, which, as above explained, is in circuit connection with the magnet coils.

If desired the contacting points of screw 43, and strip 37, may be of platinum, or 110 other suitable material, as indicated at 50.

The operation is very simple. When current is supplied to the contact screw 43, it flows to spring 37, and thence through the various contact and clamping plates, or 120 screw 33, to contact plate 18, and lug 24, to and through the magnet coils, thereby energizing the magnets and causing the armature 28, to be attracted, and hence, by reason of the finger 45, engaging over the end of 125 strip 37, causing said strip to be drawn away from the contact screw 43, thereby breaking the circuit. Thereupon the spring support of the strip 37, and of the armature 28, the latter being no longer attracted since the cir- 130

cuit is broken and the magnets deenergized, rock back again into position for the spring 37, to again contact with screw 43, thereby reestablishing the circuit and again energizing the magnet and attracting the armature.

Since the parts constituting the magnet and its coils are of permanent structure they seldom if ever require renewal or replacement, but the parts of the vibrator or circuit breaker are more delicate and hence repairs thereto and renewals or replacements thereof are frequently required. With the construction and arrangement above described such renewals, replacements and repairs may be readily and quickly effected by simply removing the attachment plate, and with it the parts carried thereby, and substituting a new one in its place thereby enabling the defective attachment to be returned to the shop and repaired at leisure. Thus it will be seen that such renewals and replacements may be effected in the case of units of banks of coils without requiring the removal of such units from the bank.

It is obvious that many variations and changes in the details of construction and arrangement of parts might readily occur to persons skilled in the art and still fall within the spirit and scope of my invention as defined in the appended claims. I do not desire, therefore, to be limited or restricted to the exact and specific details shown and described. But

Having now set forth the object and nature of my invention, and a construction embodying the principles thereof, what I claim as new and useful and of my own invention, and desire to secure by Letters Patent is:—

1. In a spark coil, the combination with a magnet and coils, and an inclosing casing therefor, said casing having a tongue, of a vibratable attachment including a supporting plate arranged to engage beneath said tongue, circuit breaking devices carried by said plate, and means coöperating with said tongue to retain said plate on the casing on the outside of the latter, said attachment, when applied, being in circuit connection with said coils.

2. The combination with a spark coil having circuit connections and an inclosing casing therefor, said casing having a tongue, of a circuit breaker attachment including a plate, a vibrating contact supported thereon, said plate engaging beneath said tongue, and means coöperating with said tongue to secure said plate to the casing on the outside of the latter, and in circuit connection with the spark coil.

3. The combination with a spark coil and an inclosing casing therefor, said casing

having a tongue, of a circuit breaker mechanism, a carrier plate therefor, said plate engaging under said tongue and means co-⁶⁵ operating with said tongue and engaging said plate to detachably secure said plate to the casing on the outside thereof, and means for completing circuit connection between the circuit breaker mechanism and the spark ⁷⁰ coil, when the former is secured in place on the casing.

4. The combination with a spark coil, and a casing therefor, of a circuit breaker mechanism, a carrier plate upon which said mechanism is mounted, a securing tongue and a spring catch carried by the casing and adapted to detachably receive and hold said plate.

5. The combination with a spark coil and a casing therefor, said casing having an engaging tongue and a spring catch, of a circuit breaking mechanism, a supporting plate therefor, said plate arranged to be engaged by said tongue and catch whereby it is ⁸⁵ movably secured to said casing.

6. The combination with a spark coil and a casing, said casing having an engaging tongue and a spring catch, and a contact plate adapted to be connected in circuit with the spark coil, of a circuit breaker mechanism, a supporting plate therefor, said plate arranged to be engaged by said tongue and catch, whereby said circuit breaker mechanism is detachably held in coöperating ⁹⁵ electrical connection with said contact plate.

7. The combination with a spark coil and its casing, said casing having an upturned tongue and a spring catch, of a plate engaged at one end by said tongue and at the ¹⁰⁰ other end by said catch whereby said plate is removably secured to said casing, a movable armature carried by said plate, a vibratable contact strip also carried by said plate and arranged to be actuated by said armature, a circuit terminal coöperating with ¹⁰⁵ said strip, and an adjustable limit stop for said armature.

8. The combination with a spark coil and its casing, said casing having an upturned tongue and a spring catch, of a plate having a tongue to coöperate with the tongue of the casing, said plate having a shoulder or projection adapted to be detachably engaged by ¹¹⁰ said spring catch, and a circuit breaker mechanism mounted on said plate.

In testimony whereof I have hereunto set my hand in the presence of the subscribing witnesses, on this 25th day of June A. D., 1908.

CHESTER H. THORDARSON.
